WILLIAM K. FELLOWS, OF CHICAGO, ILLINOIS

FRICTION HINGE

Application filed February 18, 1929. Serial No. 340,702.

Friction hinges, beginning long ago with crude forms, have long been employed for a wide variety of uses in different kinds of installations. During recent years hinges of this type have come into gradually increasing use on the doors of buildings, more particularly in hospitals and schools as standard equipment, in office buildings for communicating doors not equipped with door closers, and for bed rooms, closets and bath rooms of hotels and residences, where they are of special advantage. While of course friction hinges in general have been more or less improved from time to time, the exacting requirements for the uses above noted have demanded further improvements in order particularly to adapt hinges of this type to such installations. For example, it is required that such hinges shall be noiseless in operation, that the frictional resistance to the swinging of the door shall be uniform throughout the swinging movement, that the friction shall be maintained substantially constant at all times, and that there shall be no likelihood of these hinges getting out of order.

A general object of the invention is to provide an improved friction hinge which will effectively meet the above noted rigid requirements, as well as having other desirable advantages. Another object is to provide a hinge of this kind in which the hinge pin is readily removable, for conveniently either hanging or demounting the door. Another object is to provide such a hinge which is adaptable to a wide variety of uses, such as upon swinging closures of various kinds, including windows, traps, scuttles, or other more or less similar devices; also for the doors of cabinets and book cases, where its action in preventing the breakage of glass is particularly desirable; and upon the doors of coaches and automobiles, which would prevent many accidents due to the swinging open of the doors, and also eliminating the usual rattle which results from wear and looseness of the ordinary coach hinges heretofore commonly used on automobiles. Further objects are convenience of manufacture, economy, simplicity, reliability, durability, strength con-

venient renewal of parts and a handsome appearance. Other objects and advantages of the invention will hereinafter appear.

The invention includes various features of construction and combination of parts, as will appear from the following description.

This invention is an adaptation to a two-knuckle hinge of the invention disclosed as embodied in a four-knuckle hinge in my co-pending companion application for Patent Serial No. 340,701 filed February 18, 1929, which became a patent of even date with this patent, and having the next preceding number. In a two-knuckle hinge, it is desirable that the hinge pin shall be held firmly and rigidly by one of the hinge knuckles, since in a two-knuckle hinge there is a tilting or rocking strain on the hinge pin, so that with a hinge pin free to rotate in both knuckles this strain would cause undue and unequal wear at localized points, which would soon be likely to result in looseness and misalignment of the two hinge knuckles relatively to each other. It is therefore usual in this type of hinge to have the hinge pin rigidly carried by one of the knuckles while the other knuckle is rotative relatively to the hinge pin.

In carrying out the invention as disclosed herein in a desirable construction, the hinge leaf carrying the knuckle which holds the hinge pin against relative rotation, may be pressed or stamped out from suitable sheet metal together and all in one piece with an inner part of this knuckle which grips the hinge pin, while a split collar forming an outer portion of this knuckle and of even length with the said inner portion, surrounds and firmly grips the inner portion so as thereby to complete this knuckle, with an end bearing surface of greater extent than would be provided by the stamped sheet metal alone. In the same hinge construction the leaf which carries the other knuckle rotatably relatively to the hinge pin, may be similarly pressed or stamped out to have in one piece therewith an outer knuckle portion or collar of oversize diameter, and having a tubular cylindrical metal sleeve or bushing fixed therein and of even length therewith, to form a part of this complete knuckle, for thereby desirably in-

creasing the extent of the friction surfaces at the ends of this knuckle.

In a hinge designed for less heavy duty, each hinge leaf together with its knuckle in one piece therewith may be stamped or pressed out from suitable sheet metal, one of these knuckles being shaped to grip and hold the hinge pin against rotation, while the other knuckle is rotatable on the hinge pin. Also, while still carrying out the invention in substantially the same manner, each of the hinge leaves together with its knuckle may be cast in one piece, so as thereby to provide bearing surfaces on the ends of the knuckles of the extent desired, in such case one of the knuckles having a bore cast therein of a shape to hold the hinge pin, while the other knuckle is provided with a cylindrical bore to rotate on the hinge pin. Also in carrying out the invention according to the disclosure herein, the transverse or cross sectional shape of the hinge pin may be changed or varied to a considerable extent while still effectively carrying out the invention; in some embodiments of the invention, however, some of these shapes being more advantageous than others.

The hinge pin, which is of the same transverse shape and size throughout its length and which has end portions projecting beyond the outer ends of the two axially aligned knuckles, is non-circular by reason of having a plurality of circumferentially equidistantly spaced circularly arcuate outer portions with intervening depressed portions, which latter may be in the form of two or more flat surfaces or may take the form of two or more longitudinal grooves, the shape of which may be varied. One of the knuckles has a non-cylindrical bore shaped to harmonize with the transverse shape of the hinge pin for thereby preventing relative rotation of the latter, although the hinge pin may slide longitudinally in this knuckle having the non-cylindrical bore. The other knuckle on the other hinge leaf is provided with a cylindrical bore for rotative movement on the hinge pin. Friction washers are carried by the hinge pin to be freely slideable thereon but which are prevented from rotating thereon by reason of having their apertures of a non-circular shape which is complementary to the non-circular shape of the hinge pin.

One of the friction washers is located between the two knuckles and another is located in contact with the outer end of the knuckle having the cylindrical bore by which this knuckle is rotatable relatively to the hinge pin. A third similar washer is located on the hinge pin in contact with the outer end of the other knuckle in which the hinge pin is non-rotatable, so that this latter washer does not serve as a friction washer but provides a smooth outer bearing surface and also completes the hinge as to its symmetrical appear-

ance. The end of the hinge pin adjacent to the latter washer has a head removably secured thereon in the form of a cap, while a cap nut is screwed over the other projecting end of the hinge pin, a spring compression washer being interposed between the head and the adjacent washer on the hinge pin and a similar spring compression washer being interposed between the cap nut and the adjacent terminal friction washer, so that this nut thereby serves for adjustably compressing both of the spring washers, for thereby varying the frictional resistance to the relative swinging of the hinge leaves.

One embodiment of the invention, together with some variations therein as to some of its parts, will now be described and thereafter the invention will be pointed out in claims, reference now being had to the drawings, in which:

Fig. 1 is an elevation of a friction hinge in which the invention is embodied, shown as installed upon a door jamb and door, with the latter in its fully open condition;

Fig. 2 is a similar enlarged view in vertical axial section on a plane indicated by the line 2-2 in Figs. 3 and 4;

Fig. 3 is a horizontal section drawn to the scale of Fig. 2 taken on the line 3-3 of Figs. 1 and 2;

Fig. 4 is a similar section on the line 4-4 of Figs. 1 and 2;

Fig. 5 is a plan view of one of the spring friction adjustment washers;

Fig. 6 is an elevation or edge view of the same spring washer;

Fig. 7 is a perspective view of one of the friction washers;

Fig. 8 shows in cross section a plurality of hinge pins of different modified transverse shape which may be employed in carrying out the invention;

Fig. 9 is a view similar to Fig. 3, showing a modification in the knuckle construction according to which the knuckle shown is of smaller diameter and has no bushing sleeve therein;

Fig. 10 is a view corresponding to Fig. 4, of the same hinge construction shown in Fig. 9, and shows a modification of the knuckle construction according to which the outer split knuckle collar is omitted;

Fig. 11 is a horizontal section corresponding to Fig. 3, but showing a slightly modified construction according to which each hinge leaf together with its knuckle is formed by casting, instead of being stamped from sheet metal as shown in the preceding views;

Fig. 12 is a horizontal section corresponding to Fig. 4, of the same hinge construction that is shown in Fig. 11.

The illustrated embodiment of the invention will now be particularly described with reference to the accompanying drawings.

Referring first more particularly to Figs. 1 to 7 inclusive, it will be noted that Figs. 1 to 4 inclusive show a portion of a usual door jamb 1 and a portion of the inner edge of a fully open door 2. The door 2 is shown as pivotally hung to the jamb 1 by means of a friction hinge embodying the present invention, comprising a jamb leaf 3 and a door leaf 4 which are countersunk and secured in place by means of screws in accordance with the usual practice and as shown in the drawings. In this particular construction, each of the hinge leaves 3 and 4, together with one of the parts of its two-part knuckle, is made from stamped or pressed sheet metal, such as steel, all in one piece.

The jamb leaf 3 has formed thereon an inner knuckle portion 5 which on its opposite sides is flattened along lines parallel with the plane of the jamb knuckle 3, thereby to provide therein a non-cylindrical bore which has two diametrically opposite bore-reducing portions, shown as flat, and two outer cylindrically arcuate portions which are diametrically opposite each other, and with the axis of this bore in the plane of the exposed outer surface of the jamb leaf 3. This inner knuckle portion 5 has thereon an outer cylindrically curved split collar portion 6 of even length therewith and which may be forced over the inner knuckle part 5 or may be formed thereon, the split in this collar 6 providing for the passage of the knuckle-carrying neck portion of the jamb leaf 3, as appears perhaps most clearly in Fig. 4. The complete knuckle on the jamb leaf 3 thus comprises these inner and outer parts 5 and 6, by reason of which a knuckle of desirably large diameter is provided, for reasons which will presently appear. In the construction and installation shown in the drawings this knuckle, by reason of its being the jamb knuckle, forms the lower knuckle of the hinge.

The door leaf 4 carries an upper knuckle in axial alignment with the above described lower knuckle. This door leaf knuckle also comprises two parts which together form the complete knuckle. An outer oversize collar part 7 of this knuckle is formed on the door leaf 4, and the inner or bearing portion of this knuckle is formed by a metal sleeve or bushing 8 of even length with the collar part 7 and rigidly fixed therein. The purpose in thus combining the outer collar 7 and the inner bushing 8 thereby to form the complete knuckle is to increase the extent of the friction surfaces provided by the ends of this knuckle. This bushing 8 may be made from a piece of steel tubing or of other suitable metal. The outer collar part 7 of this knuckle may be formed closely around the bushing 8 so as to grip the latter tightly or the collar portion 7 may be first formed and then the bushing 8 may be forced into it with a rigidly tight fit. It will be noted that the bushing 8

provides a cylindrical bore through the knuckle carried by the door leaf 4, and that the collar parts 6 and 7 of the two knuckles are desirably of the same diameter.

A non-circular hinge pin 9 which is embodied in this particular hinge construction has throughout its length two diametrically opposite outer circularly arcuate portions with two intervening diametrically opposite wide shallow grooves shown as of the shape of a widely open letter V, these grooves thus being in the form of obtuse reentrant angles. This hinge pin 9 passes axially through and at its ends projects beyond the hinge knuckles. This hinge pin has a rather snug but free sliding fit in the inner flattened knuckle portion 5 of the knuckle on the jamb leaf 3, this hinge pin 9 however being firmly and securely held by this inner knuckle part 5 against relative rotative movement as also against rocking or tilting movement, as will be evident by an inspection of Figs. 2 and 4. The upper knuckle carried by the door leaf 4 and comprising the outer and inner parts 7 and 8 is freely journaled by its inner bushing part 8 on the hinge pin 9, as will be clear from Figs. 2 and 3.

The hinge pin 9 carries three washers 10 which are locked thereto against rotation but which are slidable thereon longitudinally of the hinge pin. The holes or apertures in these washers, as is clearly shown in Fig. 7, are complementary in shape to the transverse shape of the hinge pin 9. Thus the hole through each of these washers 7 has two diametrically opposite circularly arcuate outer portions of equal extent together with two intervening diametrically opposite inwardly projecting lugs each of which forms an obtuse salient angle. These lugs fit into the above noted shallow angular grooves in the hinge pin 9, as will be clear by comparing Fig. 7 with Figs. 2 and 3.

These washers 10 are located respectively, one between the two knuckles to serve as a friction washer in cooperation with the lower end of the upper knuckle, another of such washers above the upper knuckle to form a friction washer in cooperation with the upper end of this knuckle, while the third washer is located immediately below the lower end of the lower knuckle. This latter or lowermost washer is not utilized as a friction washer, but completes the hinge as to its outer appearance and also serves to form a suitable lower bearing surface, as will presently appear. These washers 10 may desirably be made of bronze so as to afford smooth uniform frictional resistance and also to provide for a minimum of wear in frictional cooperation with the end surfaces of the steel parts of the upper knuckle on the door leaf 4, and such washers may be readily produced by a stamping operation.

In carrying out the invention, the upper

and lower projecting end portions of the hinge pin 9 are provided with head-forming members separably or removably mounted thereon, and at least one of these members should have a screw threaded engagement on the hinge pin, for thereby adjusting the amount of friction. In the construction shown, the lower projecting end portion of the hinge pin 9 below the lowermost washer 10 is provided with a removable head 11 in the form of a socketed cap which fits over the end of the hinge pin and is held thereon by means of a removable transverse pin 12 which passes through the head 11 and the lower end portion of the hinge pin 9. The upper projecting end portion of the hinge pin 9 above the uppermost friction washer 10 is screw threaded and has a cap nut 13 screwed thereon.

In order to produce a more uniform frictional resistance as well as also to provide a more effective adjustment of the amount of friction developed, a compression spring desirably in the form of a spring washer 14 is interposed respectively, between the head 11 and the adjacent lowermost washer 10, and similarly between the cap nut 13 and the adjacent uppermost friction washer 10. This spring washer 14 may have a round central hole to fit freely over the pin 9, as is shown in Fig. 5, since there is no reason for locking these washers against rotative movement on the hinge pin. This spring friction adjustment washer 14 is desirably substantially of the form of construction shown in Figs. 2, 5 and 6.

This spring compression washer 14, as is shown most clearly in Figs. 5 and 6, has an inner annular flat portion from which there projects an even number, shown as twelve, of spring tongues forming a complete circumferential series with the tongues sufficiently spaced to avoid the possibility of any interference between them in their spring action. Alternately in the series, six of these tongues are bent in one direction out of the plane of the central portion of the washer and the other alternate six tongues are similarly bent in the opposite direction, so that thereby, in the hinge construction shown in the drawings, six of these tongues, in each instance at the top and bottom of the hinge, are bent upward and the other six are bent downward, so that each of these washers 14 thereby forms a compression spring. These spring compression washers 14 are desirably of steel and may be readily stamped out.

The particular above described hinge pin 9 shown in Figs. 2, 3 and 4 has proved to be particularly effective and convenient in a friction hinge of the construction shown in Figs. 1 to 7 inclusive. The two diametrically opposite arcuate outer surfaces are of sufficient extent to provide an effective journal for the door leaf knuckle in the cylindrical bore

of its bushing 8, while the two intervening shallow angular grooves not only provide an effective anchorage for the friction washers 10 but also provide a convenient transverse shape of the hinge pin by which it may be non-rotatably and slidably held within the conveniently formed inner part 5 of the hinge knuckle on the jamb leaf 3, as should be clear from the drawings, Figs. 3 and 4 particularly.

In Fig. 8 there is shown a variety of alternative hinge pins which differ from the hinge pin 9 only in their transverse shape, which similarly to the hinge pin 9 is the same throughout their length. It will be noted that each of these hinge pins shown in Fig. 8 also similarly has a plurality of equally circumferentially spaced outer arcuate portions together with intervening depressed portions. It has been found in practice that a non-circular hinge pin having only a single depressed portion provides a less effective anchor for the hinge pin and for the friction washers, particularly the uppermost friction washer, any looseness of which would have a tendency to cause the cap nut 13 to work loose.

Any one of these alternatively shaped hinge pins shown in Fig. 8 may be utilized in the above described friction hinge construction shown in Figs. 1 to 7 inclusive, in place of the particular hinge pin 9 there shown, with only slight changes in other parts or features of the construction which directly engage and cooperate with the hinge pin. Thus it is obvious that friction washers (not shown) for these hinge pins shown in Fig. 8 should have their apertures of a shape complementary to the shape of the particular hinge pin by which they are carried, similarly in that respect to the washers 10 in their relation to the hinge pin 9. Also it will be evident that the inner part of the jamb leaf knuckle would in like manner have a bore of a different shape from that of the inner knuckle part 5, in order thereby similarly to hold the differently shaped hinge pin against rotation while providing for its sliding movement.

Beginning at the left in Fig. 8, it will be noted that the hinge pin 15 is provided with two diametrically opposite flat sides which provide for rotatively locking the friction washers thereto, and that this pin is provided with two diametrically opposite outer circumferentially arcuate portions by which this pin may form a journal in the cylindrical bearing shown as provided in the inner bushing part 8 of the upper knuckle on the door leaf 4, as above described. Also it will be noted that the transverse shape of this hinge pin 15, provided by its outer arcuate portions and its flat sides, provide for this pin 15 being non-rotatably and slidably received into the flattened bore of the inner knuckle part 5 of the lower knuckle carried by the jamb leaf 3, as above described.

The hinge pin 16, it will be noted, does not

differ greatly from the hinge pin 9, first described. This hinge pin 16 has similar outer circularly arcuate journal-forming portions diametrically arranged, while the intervening depressed portions are hollowed out on a 5 rather long arcuate curve to form wide shallow grooves which provide for rotatively locking the friction washers thereto and also for locking this pin against rotation while providing for its sliding movement in the 10 jamb leaf knuckle, which may be of the same construction shown in Fig. 4, as also the door leaf knuckle may be of the same construction shown in Fig. 3.

The hinge pin 17, it will be noted, has four 15 right angularly arranged flat sides and is provided with circularly rounded corner portions by reason of which this hinge pin may form a journal while at the same time it may be held against rotative movement, as will 20 hereinafter more particularly appear. It has been found in practice that a stamped metal inner knuckle portion, corresponding to the inner knuckle portion 5 on the jamb leaf 3, may be readily formed with a square 25 bore for effectively slidably and non-rotatably holding this hinge pin 17.

The hinge pin 18 has four equidistantly spaced circumferentially arcuate outer journal surfaces, with four intervening V-shaped 30 grooves, thereby providing for its utilization in a friction hinge substantially in the same manner as hereinbefore described with reference to Figs. 1 to 7 inclusive.

The hinge pin 19 differs from the hinge pin 35 18 only in the respect that the four grooves shown therein are of arcuate or curved shape. The manner in which this hinge pin 19 may be incorporated in a hinge construction substantially similar to that above described in 40 reference to Figs. 1 to 7 inclusive appears to be obvious from the foregoing description.

The hinge pin 20, it will be noted, has three 45 inwardly angular grooves which gradually merge on curved lines outwardly with three circumferentially curved outer journal-forming portions.

The hinge pin 21 has three circularly arcuate outer journal portions with three intervening grooves of a wide V shape.

The hinge pin 22, it will be noted, differs 50 from the above described hinge pin 20 only in having four, instead of three, inwardly angular grooves which merge into the four outer circularly arcuate journal portions.

The final hinge pin 23, it will be noted, 55 is transversely of a triangular fluted shape with three outer arcuate journal-forming portions and three intervening rounded 60 grooves, it being noted that this hinge pin 23 is in general of a shape similar to the hinge pin 21 above noted, and differs from the hinge pin 19 in having three, instead of four, journal surfaces with intervening rounded 65 grooves.

In the slightly modified friction hinge construction shown in Figs. 9 and 10, these figures are similar respectively to Figs. 3 and 4, but broken away to omit outer portions. With the exception of the modified hinge knuckles shown in Figs. 9 and 10, the 70 rest of the friction hinge construction throughout is to be considered as the same as that described with reference to Figs. 1 to 7 inclusive. The hinge knuckle 24, appearing 75 in Fig. 9, is formed by a stamping operation in its entirety directly upon the door leaf 25, this knuckle 24 having a cylindrical bore by which it is journaled directly upon the hinge pin 9. The hinge knuckle 26, shown in Fig. 80 10, is similarly formed by a stamping or forging operation of a single part formed upon and in one piece with the jamb leaf 27. This jamb knuckle 26 slidably but non-rotatively receives the hinge pin 9, substantially 85 similarly in that respect to the inner knuckle part 5 of the jamb knuckle on the leaf 3, as above described with reference to Figs. 1 to 7 inclusive. It is obvious that any of the hinge pins shown in Fig. 8 may be similarly embodied in the friction hinge shown in Figs. 9 and 10.

It will be noted that this jamb knuckle 26, 90 as shown in Fig. 10, is of circularly rounded contour throughout, thereby to have a slightly 95 appearance and to harmonize with the door leaf knuckle 24. Also it will be noted of this jamb knuckle 26, that it is pressed to a shape 100 providing opposite angular inwardly projecting portions or lugs in its bore, which 105 enter the shallow angular grooves in the hinge pin 9. The friction washers to be employed would be of similar construction to that shown in Fig. 7, but of course of correspondingly smaller outer diameter, in harmony with the smaller diameter of the hinge 110 knuckles 24 and 26. This somewhat simplified construction shown in Figs. 9 and 10 of course will provide smaller friction surfaces than the construction shown in Figs. 1 to 7 inclusive, but in some cases may be advantageously employed, for relatively small and light doors.

Figs. 11 and 12 show the adaptation of the 115 invention to the forming of the hinge leaves and knuckles by a casting operation. These Figs. 11 and 12 are similar respectively to Figs. 3 and 4, the door leaf, however, being omitted from Fig. 12. Excepting in the respects shown in Figs. 11 and 12 and now to 120 be noted, the complete friction hinge construction in other respects may be similar to that shown in Figs. 1 to 7 inclusive. In this somewhat modified construction, a cast metal jamb leaf 28 is shown as having a complete 125 hinge knuckle 29 cast thereon. Similarly a cast metal door leaf 30 has a knuckle 31 cast thereon.

It will be noted from Fig. 11 that the door leaf knuckle 31 is provided with a cylindrical 130

bore by which it may be journaled on a hinge pin having any of the transverse shapes shown in the drawings and above described. The jamb knuckle 29, however, is provided with a non-cylindrical bore for rotatively locking while providing for the sliding movement of the hinge pin, and this bore in the jamb knuckle 29 may be formed as a part of the casting operation. The particular cast metal hinge shown in Figs. 11 and 12, it will be noted, is provided with the above described hinge pin 17 shown in Fig. 8, this hinge pin 17 being in general of square transverse shape with circularly rounded corners by which it forms a journal for the door leaf knuckle 31. This hinge pin 17 is non-rotatably but slidably mounted in a square hole through the jamb leaf knuckle 29. This modified hinge construction shown in Figs. 11 and 12 indicates that the invention may be substantially equally well carried out in a hinge having stamped metal parts, or in a hinge having cast metal parts, as desired or as may be required for different installations.

The operation is substantially the same in the complete construction shown in Figs. 1 to 7 inclusive and in the slight modifications thereof shown in the remaining figures of the drawings. Compression to the desired extent may be applied to both of the spring compression washers 14 by adjusting the cap nut 13 on the screw threaded upper end of the hinge pin 9. These two spring compression washers 14, acting together as a pair, press the uppermost friction washer 10 into frictional engagement with the smooth flat upper end surface of the door leaf knuckle comprising the outer collar part 7 and the fixed bushing 8, and at the same time draw this knuckle downward thereby to bring its lower smooth flat end into frictional engagement with the upper surface of the friction washer 10 which is on the hinge pin 9 between the two knuckles, the weight of the door also supplementing the frictional engagement at this middle point.

It will thus be seen that the hinge knuckle on the door leaf 4 rotates between these two friction washers 10 which are held rotatively stationary by the hinge pin 9. The spring compression washers 14 automatically take up wear on the friction surfaces. Also the amount of frictional resistance may be adjusted either for taking up wear or for varying this resistance as may be desired by adjusting the cap nut 13, thereby correspondingly to vary the amount of compression to which the spring washers 14 are subjected. It should be obvious from the drawings that the entire hinge construction may be conveniently assembled and may at any time be as readily taken apart for the convenient renewal or replacement of any parts thereof which may in time have become worn.

In a two-knuckle hinge it is desirable that

the door leaf knuckle shall be above the jamb leaf knuckle, so that the latter will support the former with the weight of the door, as shown in the drawings. It may be noted, with reference to Figs. 1 and 2, that if the hinge were turned around or rotated 180° in the plane of these figures, with the leaf 3 then attached to the door 2 and the leaf 4 attached to the jamb 1, the general appearance of the hinge would be the same and the operation in general would be substantially the same. In that case the hinge pin arrangement would simply be reversed, the hinge pin then being fixed in to rotate with the door knuckle and rotatable in the jamb knuckle, with the swinging of the door. However, for a door mounted to swing in the opposite direction to that shown, a hinge of a correspondingly reversed construction would be employed, so that its leaves would then open and close in the opposite direction from that shown.

A friction hinge embodying the invention substantially as disclosed herein is suitable for installation on casement windows; also on the doors of automobiles.

It is obvious that various modifications may be made; for example, the hinge pin might be shaped as a long spiral, without any change in the manner of operation.

It will be noted that the spring washers 14 bring an even circumferential pressure to bear, which is of particular importance in evenly distributing the wear and friction around the upper friction washer 10 and the upper end of the knuckle on the door leaf 4.

It should be further noted that the fixed or non-rotatable non-circular hinge pin, which at the same time forms a journal for the door leaf knuckle and locks the friction washers which cooperate therewith, is readily removable merely by screwing off the cap nut 13. Thus the door may be easily and conveniently either mounted or demounted, which is a matter of considerable importance in the hanging of a door.

It is obvious that various modifications may be made in the friction hinge construction shown in the drawings as an embodiment of the invention and above particularly described, within the principle and scope of the invention as defined in the appended claims.

I claim:

1. In a friction hinge, the combination of a pair of hinge leaves, a single hinge knuckle carried by each said leaf in axial alignment with the knuckle on the other leaf, one of the said knuckles having a cylindrical axial bore and the other knuckle having a non-cylindrical axial bore, a non-circular hinge pin passing through both knuckles and projecting from the ends thereof and locked against rotation in the said knuckle having the non-cylindrical bore by the engagement of the pin.

with the bore, a friction washer slidably but non-rotatably mounted on the hinge pin between the knuckles, another friction washer similarly slidably and non-rotatably mounted 5 on the hinge pin immediately outward from the said hinge knuckle having the cylindrical bore, and terminal members on the projecting ends of the hinge pin one of which is a nut for drawing the friction washers and knuckles 10 into frictional engagement thereby to provide frictional resistance to the relative swinging of the hinge leaves.

2. In a friction hinge, the combination of a pair of hinge leaves, a single hinge knuckle 15 carried by each said leaf in axial alignment with the knuckle on the other leaf, one of the said knuckles having a cylindrical axial bore and the other knuckle having a non-cylindrical axial bore, a non-circular hinge pin passing through both knuckles and projecting 20 from the ends thereof and locked against rotation in the said knuckle having the non-cylindrical bore by the engagement of the pin with the bore, a friction washer slidably but 25 non-rotatably mounted on the hinge pin between the knuckles, another friction washer similarly slidably and non-rotatably mounted on the hinge pin immediately outward from the said hinge knuckle having the cylindrical 30 bore, terminal members on the projecting ends of the hinge pin one of which is a nut for drawing the friction washers and knuckles into frictional engagement thereby to provide frictional resistance to the relative swinging 35 of the hinge leaves, and a compression spring adjacently inward from one of the said terminal members thereby to be subjected to compression by the said nut so that thereby the said frictional resistance will be 40 applied through the said spring.

3. In a friction hinge, the combination of a pair of hinge leaves, a single hinge knuckle carried by each leaf in axial alignment with the knuckle on the other leaf, one of the 45 knuckles having through it an axial cylindrical bore and the other knuckle having through it an axial non-cylindrical bore providing in such bore circumferentially spaced inwardly extending bore-reducing portions and cylindrically arcuate outer portions in the bore and extending throughout the length of this knuckle, a non-circular hinge pin having throughout its length circularly arcuate outer portions with intervening depressed portions 50 so that such hinge pin is thereby rotatively locked in the knuckle having the non-cylindrical bore, said hinge pin projecting at its ends beyond the knuckles, a head removably fixed upon the projecting end of the hinge 55 pin adjacent to the knuckle having the non-cylindrical bore, a friction washer slidably and non-rotatably mounted on the hinge pin between the knuckles, another friction washer similarly slidably and non-rotatably mounted 60 upon the projecting end portion of the hinge 65

pin immediately adjacent to the outer end of the knuckle having therein the cylindrical bore, and a nut screwed over the end of the hinge pin adjacent this latter friction washer for drawing together the knuckles and friction washers thereby to provide frictional resistance to the relative swinging of the hinge leaves.

In witness whereof, I hereunto subscribe my signature.
